W. E. KAY,
PROTECTED PNEUMATIC HEEL,
APPLICATION FILED FEB. 15, 1919.

1,342,291.

Patented June 1, 1920.

UNITED STATES PATENT OFFICE.

WILLIAM EDWARD KAY, OF ELYRIA, OHIO.

PROTECTED PNEUMATIC HEEL.

1,342,291.

Specification of Letters Patent.

Patented June 1, 1920.

Application filed February 15, 1919. Serial No. 277,236.

To all whom it may concern:

Be it known that I, WILLIAM EDWARD KAY, a citizen of the United States, and resident of Elyria, in the county of Lorain and State of Ohio, have invented certain new and useful Improvements in Protected Pneumatic Heels, of which I hereby declare the following to be a full, clear, and exact description, such as will enable others skilled in the art to which it appertains to make and use the same.

The objects of the invention are to provide a pneumatic heel in which air is confined under pressure, and in which the amount of resiliency is variable under variable pressure and according to the weight of the individual wearing it. For this reason the amount of resiliency can be determined by the size of the pneumatic chamber and will vary naturally with the weight of the wearer.

One of the important features of the improvement and novelty is found in the fact that the weight will be evenly and regularly distributed over the entire wearing surface of the heel, which is not true of heels of cushion or other types.

Another important feature is found in the protection afforded to the resilient body of the heel by the replaceable tread member employed, and the fact that the wearing portion is always renewable without disturbing the body of the heel.

The invention comprises a heel composed of solid rubber or other elastic and vulcanizable substance, and containing a pneumatic chamber or cavity. Also an air tight closure is provided for this chamber, by means of which a predetermined amount of pressure can be given the air in the chamber.

The invention further consists in the combination and arrangement of parts and construction of details hereinafter described, shown in the accompanying drawings and specifically pointed out in the claims.

In the accompanying drawings, Figure 1 is a longitudinal vertical section of the heel. Fig. 2 is a transverse section thereof on line $x-x$ Fig. 1. Fig. 3 is a section of the removable tread plate. Fig. 4 is a perspective of a modified form and Fig. 5 is a vertical section on center line Fig. 3.

In these views A represents a heel body, formed preferably of solid rubber and containing a cavity B which is open below on the tread side. This body is attached to

the sole C of the shoe by rivets, or clinch nails D, the heads of which are concealed in openings E.

Reinforcing the open edge of the cavity B, is shown a thin metal band F, which is anchored in the body A, by means of the backwardly rolled or turned edges G.

The closure for this cavity is shown to be a heavy leather or composition tread plate H which is provided with an engaging flange or complementary annular band I, which projects upwardly and forms an air tight joint with the metal band E when their bearing surfaces are forced together.

This metal band I may be formed integrally with a metal plate J, which is attached to the plate H by rivets K, K, as shown in Figs. 1 and 2 or it may be molded into the raised body H' of the plate H, as shown in Figs. 3 and 4.

In either case when the parts are forced together the bearing surfaces of the bands make the emission of air impossible.

When the raised center H' of the tread plate H is employed the air within the chamber B will be compressed, which will lessen the amount of resiliency according to the sectional area displaced, and hence by varying the amount of penetration of the body the amount of resiliency can be varied to suit different purchasers.

Having described the invention what I claim as new and desire to secure by Letters Patent is:

1. The combination with a resilient heel body, said body provided with a cavity opening on the underside thereof; a metallic reinforcing band encircling the outer edge of said cavity, a metallic inner band, insertible in said reinforcing band in air tight relations therewith, and a tread plate adapted to receive the wear upon said heel, said tread plate and inner band attached together.

2. A pneumatic heel comprising, a resilient body, having an opening in its lower face, a separate tread member covering the tread side of said body and said opening, an annular metal band secured to said tread member and entering said opening, and a complementary annular metal band secured to the margin of said opening, said bands making air tight contact with each other.

3. A pneumatic heel comprising, a resilient body, having an opening in its lower face, a separate tread member covering the

- 2
- tread side of said body and said opening, an annular metal band secured to said tread member and entering said opening, and a complementary annular metal band secured 5 to the margin of said opening, said bands making air tight contact with each other, the inner edge of said marginal band in said opening being outwardly turned and embedded in the said resilient body.
- 10 4. A pneumatic heel comprising a resilient heel body, having a pneumatic cavity therein, a tread plate covering said cavity, complementary annular metallic bands detachably sleeved together and making an air tight contact with each other, one of said bands secured to said tread plate and the other band secured to the vertical wall of said opening within the same, and means for securing said bands in their respective positions.
- 15 5. In a heel, a resilient body provided with a pneumatic cavity, a tread plate thereover, complementary annular sleeved members on said body and plate respectively 20 providing an air excluding connection therebetween and means for securing said complementary members in their respective positions.
- 25 6. A pneumatic heel body comprising a hollow resilient heel body having air opening in the bottom or tread side, a separate tread member covering the tread side of said body and opening, and means attached to 30
- said tread member for forming an air tight closure for said opening. 35
7. In a heel, a resilient body provided with an opening in its lower face, a tread plate secured thereto, an annular metal band secured upon one edge to said plate, a complementary annular metal band secured to 40 the inner face of said opening, said annular bands making air tight engagement with each other, and filling means for said annular band on said tread plate. 45
8. A pneumatic heel comprising a resilient heel body, having an opening in its tread side, and a detachable tread member covering said tread side and opening, and means attached to said tread member and insertible in said opening for making an air 50 tight joint therewith.
9. A pneumatic heel comprising a resilient heel body having a cavity in its tread side, a metal annular bearing member in the outer edge of said cavity, a detachable tread member applied to the tread side of said heel, and a corresponding annular bearing member attached to said attachable tread member. 55
- In testimony whereof I hereunto set my hand this 4th day of Feb., 1919.
- WILLIAM EDWARD KAY.
